UNITED STATES PATENT OFFICE.

EDGAR L. DRYDEN, OF COLLEGE SPRINGS, IOWA.

DESIGN FOR A CLOTHES-PIN.

SPECIFICATION forming part of Design No. 34,757, dated July 9, 1901.

Application filed May 9, 1901. Serial No. 59,541. Term of patent 7 years.

To all whom it may concern:

Be it known that I, EDGAR L. DRYDEN, a citizen of the United States, residing at College Springs, in the county of Page and State of Iowa, have invented and produced a new and original Design for a Clothes-Pin, of which the following is a specification.

This invention relates to a design for a clothes-pin, and the essential features reside

in the clothes-pin as illustrated in the accompanying drawings, wherein—

Figure 1 is a perspective view of a clothes-pin embodying the features of the design.

Fig. 2 is a top plan view of the same. Fig. 3
5 is a side elevation thereof.

The design is characterized by oppositely-extending arms 1, continuing from upwardly-projecting curved members 2, which have their upper terminating portions 3 at reverse 20 inward angles to each other and merging into a central coil 4 in a plane at a right angle to

the planes of the said members 2. The coil 4 lies within the confines of the upwardly-projecting members 2, the latter unitedly presenting an approximate heart-shaped central 25 portion. At the point where the arms emanate from the lower portions of the members 2 they cross each other, and at their outer ends said arms have reversely-directed hooks 5, open at the bottom.

Having thus described the invention, what is claimed as new is—

The design for a clothes-pin, as herein shown and described.

In testimony that I claim the foregoing as 35 my own I have hereto affixed my signature in the presence of two witnesses.

EDGAR L. DRYDEN.
